UNITED STATES PATENT OFFICE.

HENRY R. BOETTCHER, OF CHICAGO, ILLINOIS.

ANIMAL-SHEARS.

No. 832,836.

Specification of Letters Patent.

Patented Oct. 9, 1906.

Application filed March 28, 1906. Serial No. 308,436.

To all whom it may concern:

Be it known that I, HENRY R. BOETTCHER, a citizen of the United States, residing at Chicago, in the county of Cook and State of Illinois, have invented a new and useful Improvement in Animal-Shears, of which the following is a specification.

My invention relates to an improvement in the class of animal-shears exemplified in United States Letters Patent No. 442,239, dated December 9, 1890, and while not intending to limit my improvement to that particular machine, since it may be used to advantage with other constructions of machines in the same class, I have selected the machine of the aforesaid patent for illustrating my invention in the accompanying drawings, in which—

Figure 1 is a broken view in longitudinal vertical section of the entire device; Fig. 2, a plan view of the forward operating-end portion of the device to which my improvement is applied, and Fig. 3 a perspective view showing in unassembled relation the parts constituting my improvement.

The object of my invention is to provide a novel construction of bearing-bracket which shall render it peculiarly simple and effective in producing desirable uniform bearing against the surface of the comb of the cutter-bar, which vibrates across it to perform the cutting operation, notwithstanding any irregularity in the said surface or in the under or upper surface of the cutter-bar.

The fact is recognized in the art to which my invention relates that for practicability in the operation of the shears the cutter-bar should have at least three bearing-points on the comb-surface, or, in other words, that at least three cutting-teeth are required in the set thereof with which the bar is formed. This surface of the comb and the under surface of the cutter-bar are frequently irregular, inclining from a perfectly level plane, with the effect of presenting the bearing-points of the bracket for pressing the teeth against the comb on different planes, and thereby rendering the pressure non-uniform, while it should be uniform to prevent binding of the cutter in operation and other imperfect action. To avoid these difficulties, it is common to provide a bracket engaging the cutter-bar at different points thereon to tighten it against the comb-surface, with one of the bearing-points of the bracket adjustable in-

dependently of the others; and my invention relates, primarily, to a novel construction of the bracket for rendering such bearing-points thereof independently adjustable.

In the drawings, A is the casing, containing the operating mechanism and provided with a removable cover A³, a bearing for the front end of the rotatory operating-shaft B, and a handle A', extending from the bearing, the rear end of which is cylindrical and internally screw-threaded to receive a bushing C², forming the bearing for the rear end of the shaft. Loosely mounted on the handle is a sleeve C', containing a circumferential rib c', fitting against the handle and the rear end of the bushing, having a flange c² to bear against the rear face of a rib (not shown) on the sleeve C' to hold it against endwise motion. A pinion C³ is housed in the rear screw-threaded end of the shaft and meshes with a pinion C³³ on the end of a short driving-shaft C⁴, to which the flexible shaft for actuating the device may be attached in any suitable manner. On the shaft C⁴ is a sleeve C⁵, pivotally connected with the sleeve C' to enable it and its contained shaft to assume any inclination relatively to the shaft B without throwing the pinions out of gear. At its forward end the shaft B carries a crank D, on the pin D' of which is loosely mounted a roller D², of hard steel-working in a rectangular bearing E², which is detachably connected with the vibrating lever E. A fulcrum-pin on the rear end of the lever is loosely stepped into the casing at E'. From the forward end of the lever project the studs d and d' for a purpose hereinafter explained. H is the comb, which is rigidly secured to the forward end of the casing, and F is the cutter-bar, which is vibrated across the comb, the cutter-bar being provided with three teeth, as represented.

The parts thus far described, except the vibratory lever, are the same as the corresponding parts of the structure set forth in the aforesaid Letters Patent and are herein identified by the same reference characters as those in the patent.

G is my improved bearing-bracket, consisting of two sections e and e', the former having a recess in its inner end and being provided with bearings f and f' at its ends to coincide, respectively, with an outer end tooth and the central tooth of the cutter-bar F, and the section e' having a tongue e² projecting from its inner end to enter the recess

in the section e and at which the sections are hinged or pivoted endwise together by a pin e^3 and the section e' having a bearing f^2 to coincide with an end tooth of the cutter-bar.

5 The opening in the tongue e^2 , through which the pivot-pin e^3 passes, is shown larger than the pin to permit free and independent rocking of the bracket-sections. The bracket G seats on the cutter-bar, with which it is connected, as usual, by pins or screws $g\ g$ in its ends registering with and entering holes in the end portions of said bar. For attaching the bracket to the lever E the studs d and d' are provided on the latter to enter and fit loosely in holes $h\ h$, provided to receive them in the sections $e\ e'$, which are thus free to rock on the studs, and to fasten the bracket against slipping off the studs I provide as a preferred means for the purpose a circumferential recess d^2 in the stud d to admit a screw d^3 , passed through an opening d^4 in the top of the bracket-section e and with which the recess d^2 registers when the parts are assembled. It is not essential that the sections e and e' be fastened together, as they may be loosely joined by the tongue-and-recess engagement.

Means for adjusting the degree of pressure exerted by the cutter-bar on the comb are shown to be provided, being the same as in the aforesaid patent and described as follows: A hard-steel step E^7 is detachably seated in the lever E in advance of the bearing E^2 . An adjusting-plug A^2 works in a screw-threaded opening in the cover A^3 and is provided with a head A^4 and with a socket a^2 , being held against rotation by the toothed end of a spring A^5 , supported on the cover to engage said head. The under face of the plug A^2 bears against the head of a hard-steel pin I of cone shape, the upper face of which is a segment of a sphere and the lower end of which works in the step E^7 on the lever E .

The construction of the bracket G renders it flexible, and by pivotally supporting the sections forming it on the lever E they are rendered independently adjustable to automatically adapt themselves against the parts of the cutter-bar on which they bear. The bracket thus serves under the action of the plug A^2 and pin I against the lever E to tighten the cutter-bar against the comb, and if the upper and lower surfaces of the bar and the coöperating surface of the comb are level the bearing-points of the bracket G will be depressed uniformly and simultaneously by tightening the plug A^2 ; but if one or more of the said surfaces should be irregular the bracket-sections by rocking on their supporting-studs will adjust themselves against the cutter-bar in a manner to compensate for such irregularities and tighten the bearing-points of the bracket uniformly against the bar to conform the under surface of the latter to the coöperating surface of the comb and

effect even action of the cutter-bar throughout its vibratory movement against the comb-surface.

What I claim as new, and desire to secure by Letters Patent, is—

1. In animal-shears, the combination with the comb and the vibratory cutter-bar co-operating therewith, of a bearing-bracket engaging said bar to tighten it against the comb-surface, said bracket being formed of sections flexibly joined together near adjacent ends, for the purpose set forth. 70

2. In animal-shears, the combination with the comb and the vibratory cutter-bar co-operating therewith, of a bearing-bracket engaging said bar to tighten it against the comb-surface, said bracket being formed of a section having a recess in one end and a section having a tongue entering said recess and at which the sections are flexibly joined together, for the purpose set forth. 80

3. In animal-shears, the combination with the comb, the vibratory cutter-bar coöperating therewith, and the vibratory operating-lever, of studs projecting from the forward end of said lever, a bearing-bracket formed of flexibly-joined sections each journaled on one of said studs, and means for adjusting said lever to engage said bracket with the cutter-bar for tightening said bar against the 90 comb-surface, for the purpose set forth.

4. In animal-shears, the combination with the comb, the vibratory cutter-bar coöperating therewith, and the vibratory operating-lever, of studs projecting from the forward 100 end of said lever, a bearing-bracket formed of a section having a recess in one end and a section having a tongue entering said recess and at which the sections are flexibly joined together, each of said sections being journaled on one of said studs, and means for adjusting said lever to engage said bracket with the cutter-bar for tightening said bar against the comb-surface, for the purpose set forth. 105

5. In animal-shears, the combination with the comb, the vibratory cutter-bar coöperating therewith, and the vibratory operating-lever, of studs projecting from the forward end of said lever, one of said studs having a recess, a bearing-bracket formed of a section 115 having a recess in one end and a section having a tongue entering said recess and at which the sections are pivotally connected together, holes in said sections into which said studs extend, a screw working in one of said sections and engaging said stud-recess, and means for adjusting said lever to engage said bracket with the cutter-bar for tightening said bar against the comb-surface, for the purpose set forth. 120
